INVENTOR:
Julius Rumpel,

BY
F. G. Fischer
ATTORNEY

UNITED STATES PATENT OFFICE.

JULIUS RUMPEL, OF WESTON, MISSOURI.

RECEPTACLE.

1,130,932.

Specification of Letters Patent. Patented Mar. 9, 1915.

Application filed June 8, 1914. Serial No. 843,696.

To all whom it may concern:

Be it known that I, JULIUS RUMPEL, a citizen of the United States, residing at Weston, in the county of Platte and State 5 of Missouri, have invented certain new and useful Improvements in Receptacles, of which the following is a specification.

My invention relates to improvements in lunch receptacles, and my object is to provide a simple device of this character, wherein lunches and cold drinks may be conveniently packed for picnic parties, etc.

The receptacle has an ice compartment and is made of air and waterproof material, 15 so that when provided with ice and refreshments the same will be kept cold and fresh for a considerable period of time.

The device is made of inexpensive material, so that it may be thrown away after use 20 if desired.

In order that the invention may be fully understood, reference will now be made to the accompanying drawing, in which:

Figure 1 is a perspective of the receptacle 25 open ready for filling. Fig. 2 is a perspective of the receptacle closed. Fig. 3 is a section on line III—III of Fig. 2.

In carrying out the invention, I employ a box 1, made, preferably, of pasteboard or 30 other stiff material.

2 designates an extensible top for the box 1, said top being made, preferably, of paper which can be readily folded into closed position as disclosed by Figs. 2 and 3, for the 35 purpose of excluding air from the receptacle and contents thereof. One margin of the top 2 has a flexible metallic clip 3, suitably secured thereto to secure the top in closed position.

40 4 designates a perforate ice compartment arranged within box 1. Perforations 5 in said compartment are located some little distance above the bottom thereof, so that water accumulating from the melting ice will 45 not overflow into the balance of the box 1.

The box 1 and its top 2 are, preferably, treated with waterproofing material, so that no damage will ensue should the water from the melting ice come into contact with said 50 box 1 and its top 2. However, when food likely to be spoiled by water from the melt-

ing ice is packed in the box 1, I provide a cap 6 to fit snugly over the walls of the compartment 4, to retain the water in the latter.

The bottom of the box 1 is reinforced by a strip of stiff material 7, extending across said bottom and secured to the box by a fabric bail 8, pasted or otherwise secured to said strip 7 and two sides of the box 1.

In practice, ice is placed in the compartment 4, while edibles and bottles containing liquid refreshments may be packed around and over said compartment, the whole being firmly secured in place by bringing the 65 opposite sides of the top 2 together, and then rotating the clip 3 downwardly to wind the two sides of the top thereon, after which the projecting ends of the clamps are folded toward each other, as disclosed by Fig. 2, to 70 prevent the top from unwinding or unfolding.

By making the top 2 of flexible material extending some distance above the top of the box 1, the capacity of the receptacle may be 75 enlarged or diminished according to the number of times said top is folded around the clip 3.

While I have shown and described the preferred form of my invention, I of course, 80 reserve the right to make such changes in the construction, combination, and arrangement of parts as properly fall within the spirit and scope of the claims.

Having thus described my invention, 85 what I claim and desire to secure by Letters Patent, is:

A box, a compartment of waterproof material mounted upon the bottom of the box and having a series of spaced rows of perforations formed therein, the lowermost row of perforations being spaced above the bottom of the compartment, and a cap detachably engaged over the compartment for covering the perforations to prevent liquid 95 from the compartment entering the box.

In testimony whereof I affix my signature, in the presence of two witnesses.

JULIUS RUMPEL.
